(57) **CLAIM**

The ornamental design for an electric cleaning equipment for animal, as shown and described.

DESCRIPTION

FIG. 1 is a top, front, left side perspective view of an electric cleaning equipment for animal, showing my new design; FIG. 2 is a bottom, rear, right side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1; and,

FIG. 10 is an enlarged view of a portion labelled 10 in FIG. 2.

The broken lines in the drawings depict portions of the electric cleaning equipment for animal that form no part of the claimed design.

The dash dot dash lines in FIG. 1, FIG. 2, FIG. 9 and FIG. 10 are for the purpose of depicting the cut line of the enlarged view and form no part of the claim.

1 Claim, 10 Drawing Sheets
